PORTABLE LAMP

Rudolf Popp, Valparaiso, Ind., assignor to McGill Manufacturing Company, Inc., Valparaiso, Ind., a corporation of Indiana

Application October 30, 1943, Serial No. 508,273

3 Claims. (Cl. 240—54)

1

The present invention relates to portable lamps and more particularly to improvements in portable lamps of the so-called vapor sealed type. This application is a continuation in part of co-pending application Serial No. 503,595, filed September 24, 1943.

Portable lamps of the so-called vapor sealed type employing parts formed of insulating material have long been manufactured for use in areas where static discharges or arcs are to be avoided, due to the presence of inflammable or explosive gases. In a portable lamp of this character, it is particularly important to insulate the lamp bulb against mechanical shock and vibration, not only for the purpose of minimizing filament breakage, but also to minimize the likelihood of envelope breakage, and, hence, the possibility of gas or vapor ignition. From the standpoint of manufacturing cost, it is also desirable not to employ complicated sealing and shock insulating facilities in the construction of a portable lamp of this type.

It is an object of the present invention, therefore, to provide an improved and simple structure for housing the bulb of a portable lamp within a sealed transparent enclosure.

It is another object of the invention to provide an improved and simple arrangement for minimizing the transmission of mechanical shock and vibration to the bulb receiving socket through the handle of the device.

According to another object of the invention, at least one of the parts of the sealing structure is also utilized to insulate the lamp receiving socket against shock and vibration occasioned by contact of the portable lamp handle with other objects.

The invention, both as to its organization and method of operation, together with further objects and advantages thereof, will best be understood by reference to the following specification taken in connection with the accompanying drawing, in which:

Fig. 1 is a side view, partially in section, illustrating a portable lamp holder provided with improved sealing and shock insulating facilities characterized by the features of the present invention;

Fig. 2 is a top sectional view of the device shown in Fig. 1; and

Fig. 3 is a fragmentary sectional view of a modified sealing and shock insulating structure also characterized by the features of the present invention.

Referring now to the drawing and more par-

ticularly to Figs. 1 and 2 thereof, the portable lamp there illustrated comprises a handle 10 which is formed of hard insulating material, such as molded Bakelite or the like, capable of transmitting mechanical shock and vibration. At its upper end, the handle 10 is provided with a flared or enlarged portion 10a having an opening 10b extending longitudinally thereof for receiving an incandescent lamp socket 35. Integrally formed, 5 radially extending ribs 13 are provided around the circumferential surface of the handle portion 10a, which have countersunk openings 14a therethrough for receiving assembly screws 14 in a manner such that the heads of the screws are not exposed. These screws may be utilized rigidly to support the base 15 of a lamp guard 16 upon the upper platform-like surface of the handle 10 in the manner illustrated. For the purpose of preventing the screws 14 from becoming disassembled from the handle 10 during disassembly 10 of the handle and guard, each opening 14a is counterbored from the top, as indicated at 14b, to receive a fibre washer 14c which is threaded onto the associated screw 14. More specifically, 15 each washer 14c is threaded onto the associated screw 14 to a point where it will be disposed only slightly below the undersurface of the guard base 15 when the guard is supported upon the upper surface of the handle. A tight thread fit is utilized 20 in each screw and washer assembly in order to insure rotation of the two parts as a unit and thus prevent the washer from working loose from the screw. With this arrangement, the screws 14 are loosely locked to the handle when the guard 25 is disassembled therefrom, thereby to prevent the screws from becoming lost and to facilitate assembly of the guard upon the handle.

The opening 10b through the handle 10 is also utilized to receive the conductors of a cord 11, 40 these conductors being connected in the customary manner to the terminals of the lamp socket 35. At its lower end, the handle 10 is provided with a tapped longitudinally extending opening 45 for receiving the external threads of an anchor cap 12, which is also formed of insulating material. This cap is drilled to provide an opening 12a of slightly greater diameter than the cord 11 and is then counterbored through the threaded end portion thereof to provide an annular space 12b 50 surrounding a section of the cord. Adjacent the upper end of the cap, the handle 10 is provided with a transversely extending portion 10c having an opening 10d therethrough which is of the same diameter as the opening 12a. A soft rubber sleeve 55 8 is disposed within the annular space 12b and

is of greater length than this space, so that as the cap 12 is threaded into the tapped end of the handle 10, the end portions of the sleeve are extruded within the spaces between the cord 11 and the walls of the two openings 10d and 12a, and the intermediate portions of the sleeve are swelled against the cord 11 and the sides of the bore 12b. Thus the cord 11 is fixedly anchored within the cap 12 and a hermetic seal is provided for preventing gases or liquids from entering the hollow portion 10b of the handle through the cord opening.

For the purpose of enclosing a bulb 31, with which the device is fitted, within a sealed gas-tight chamber, a bulb enclosing globe 30 is provided. This globe is in the form of an inverted cup, is constructed of shatter-proof glass having heavy wall thickness, and half of the area thereof is enameled or otherwise coated as indicated at 30a to provide a light reflecting surface. At the outer side of the rim portion thereof, the globe 30 is provided with threads 30b which are adapted for engagement with internal threads 10e formed in the inner peripheral surface of the recessed end portion of the handle 10. More specifically, the enlarged upper portion 10a of the handle 10 is provided with an enlarged cup-shaped opening at which the socket receiving opening 10b terminates. Around the mouth of the socket receiving opening 10b, an annular recess 37 is formed to receive a flexible washer 38 made of soft rubber or the like, in the manner more fully explained below. A flat platform-like surface 10f extending transversely of the handle 10 is thus provided between the walls of the enlarged cup-shaped opening and the edge of the recess 37. For the purpose of providing a sealed connection between the globe 30 and the handle 10, a soft rubber washer 32 is laid within the cup-shaped recess flat against the surface 10f. This washer is of such dimensions that the outer edge surface thereof is disposed between the edge of the globe 30 and the surface 10f to be clamped therebetween when the globe 30 is threaded into the threaded portion of the handle 10. Thus, a hermetic seal is formed between the lip of the globe 30 and the handle 10. This seal, in cooperation with the seal provided by the soft rubber sleeve 8, functions to prevent inflammable gases or vapors from entering the chamber within which the bulb 31 is disposed.

As indicated above, the soft rubber washer 38 is utilized resiliently to support the bulb receiving socket 35 within the apertured portion 10b of the handle 10. More specifically, the washer 38 entirely fills the annular recess 37 and is partially covered by the inner edge portion of the washer 32. At the upper inner edge thereof, it seats the annular rim or flange portion 35a of the lamp socket 35 in a manner such that the side walls of the socket are displaced from and out of contact with the surface of the opening 10b within the handle 10. The outer periphery of the socket flange is snugly embraced within the inner periphery of the washer 32, whereby this washer assists in maintaining the socket 35 located in a position centrally of the opening 10b and out of contact with the handle 10. The flange portion of the socket 35 is clamped to the handle 10 through the flexible washer 38 by means of assembly elements 34 which bear against the upper surface of the socket flange 35a, overlie the rubber washer 32, and are held in clamping engagement with the upper edge of the socket by clamping screws 33 which are threaded into the flared portion 10a

of the handle 10. Thus, a simple arrangement is provided for sealing the bulb 31 within the globe 30 and for minimizing the transmission of mechanical shock or vibration to the bulb through the socket 35 when the device is dropped or is brought into contact with a vibrating object.

The modified structure shown in Fig. 3 of the drawing is substantially similar to that just described, the principal difference being that in the Fig. 3 arrangement the soft rubber washer 32 serves the two functions of providing a hermetic seal between the handle 10 and the globe 30, and of resiliently supporting the lamp socket 35 within the handle 10 to minimize the transmission of mechanical shock or vibration to the lamp bulb 31. In order to enhance the action of the rubber washer 32 in performing the last-mentioned function, this washer is provided with an up-standing annular portion 32a of greater longitudinal thickness than the remaining portions of the washer. At the upper edge thereof, the washer portion 32a supports the annular rim of the lamp socket 35 in a manner such that the side walls of the socket are displaced from the inner surface of the opening 10b within the handle 10. Assembly screws 33 and clamping elements 34, in combination with spacing columns 36, are utilized to clamp the socket rim 35a to the platform surface 10f of the handle 10 through the thickness of the annular washer portion 32a. More specifically, each spacer column 36 is in the form of a sleeve telescoped over one of the assembly screws 33 and is provided with a tapering upper surface, such that a knife edge support is provided for the associated clamping element 34 at the end thereof farthest removed from the peripheral edge of the socket flange 35a. Thus, a simple arrangement is provided by which the lamp socket 35 is resiliently supported upon the handle 10 to prevent mechanical shocks from being transmitted to a bulb or lamp supported therein.

While different embodiments of the invention have been disclosed, it will be understood that various modifications may be made therein, which are within the true spirit and scope of the invention.

I claim:

1. In a portable lamp, a handle formed of hard insulating material which is capable of transmitting mechanical shock and vibration, said handle having a socket receiving opening extending longitudinally thereof and an annular recess around the mouth of said opening, a flexible washer filling said recess, a lamp socket provided with a flange portion seated upon said washer and supported within said opening solely by said washer, whereby the transmission of mechanical shock and vibration through said handle to said socket is minimized, a second flexible washer partially overlying said first-named washer and snugly embracing the periphery of said socket flange, and means including said second washer for clamping said socket to said handle through said first-named washer.
2. In a portable lamp which includes a handle provided with an enlarged portion formed of a hard material capable of transmitting mechanical shock and vibration; the combination which includes means formed integral with the enlarged portion of said handle for defining a cup-shaped recess which is concentrically arranged relative to said handle, said handle also having a socket receiving opening extending longitudinally thereof and an annular recess at the mouth of

said opening, a flexible washer filling said last-named recess, a lamp socket provided with a flange portion seated upon said washer and supported within said opening solely by said washer, whereby the transmission of mechanical shock and vibration through said handle to said socket is minimized, a second flexible washer partially overlying said first-named washer and snugly embracing the periphery of said socket flange, means including said second washer for clamping said socket to said handle through said first-named washer, a bulb enclosing globe including a rim portion extending within said cup-shaped recess so that the edge thereof bears against said second washer, and means for producing pressure engagement of the edge of said globe with said washer.

3. In a portable lamp which includes a handle provided with an enlarged portion formed of a hard material capable of transmitting mechanical shock and vibration; the combination which includes means formed integral with the enlarged portion of said handle for defining a cup-shaped recess which is concentrically arranged relative to said handle, said handle also having a socket

receiving opening extending longitudinally thereof and an annular recess at the mouth of said opening, a flexible washer filling said last-named recess, a lamp socket provided with a flange portion seated upon said washer and supported within said opening solely by said washer, whereby the transmission of mechanical shock and vibration through said handle to said socket is minimized, a second flexible washer partially overlying said first-named washer and snugly embracing the periphery of said socket flange, clamping pieces extending radially across the upper surfaces of said second washer and socket flange at points around the circumference of said socket flange, clamping screws extending through said second washer and said clamping pieces and threaded into said handle to clamp said socket to said handle through said first-named washer, a bulb enclosing globe including a rim portion extending within said cup-shaped recess so that the edge thereof bears against said second washer, and means for producing pressure engagement of the edge of said globe with said washer.

RUDOLF POPP.
